UNITED STATES PATENT OFFICE.

LOUIS H. WALES, OF NEW BRITAIN, CONNECTICUT, ASSIGNOR TO THE RUSSELL AND ERWIN MANUFACTURING COMPANY, OF SAME PLACE.

DESIGN FOR A LOCK-CASE.

SPECIFICATION forming part of Design No. 34,134, dated February 26, 1901.

Application filed January 31, 1901. Serial No. 45,518. Term of patent 7 years.

To all whom it may concern:

Be it known that I, LOUIS H. WALES, a citizen of the United States, residing at New Britain, in the county of Hartford and State of Connecticut, have invented and produced a new and original Design for a Lock-Case, of which the following is a specification, reference being had to the accompanying drawing, forming a part thereof.

The only figure of the drawing is a perspective view of a lock-case, showing my new design, the edges of the case being represented in broken lines.

The contour of the case in side view presents, mainly, a rectangular form, with slight extensions 11 upwardly and downwardly from the upper and lower corners of the edge 2. The front or broad side of the case at this edge 2 has a border-ledge 3, while there is a similar ledge 4 at the edge opposite thereto, and other ledges 5 at the top and bottom, as shown. Another ledge 6 extends from the top one of the ledges 5 to the lower one, as shown, and

divides the front or broad side of the case into two separate panels, the one nearest the edge 2 being much narrower than the other panel. The narrower panel has a long central ornament 7 of conventional leaflets, and surrounding said ornament is an angular ledge 8, with rounded ends 9. Inside of the border of the larger panel there is a row of crosslets 10 and inside of the crosslets a plain band 11 and inside of the plain band 11 an angular ledge 12. The body of this larger panel has the ornaments 13 and 14, consisting of conventional leaflets.

Having described my invention, what I claim as new, and desire to secure by Letters Patent, is—

The design for a lock-case, as herein shown and described.

LOUIS H. WALES.
